(57) **CLAIM**

The ornamental design for an electronic device display or portion thereof with a graphical user interface, as shown and described.

DESCRIPTION

The FIGURE is a front view of an electronic device display or portion thereof with a graphical user interface showing the present design.

The outermost broken-line rectangle shows the perimeter of an electronic device display or portion thereof and forms no part of the claimed design. The remaining broken lines show portions of the graphical user interface and form no part of the claimed design.

1 Claim, 1 Drawing Sheet
